UNITED STATES PATENT OFFICE.

MILTON W. ALEXANDER, OF ALBANY, AND JAMES W. BRADSHAW, OF TROY, NEW YORK, ASSIGNORS TO UNIVERSAL BRUSH COMPANY, OF TROY, NEW YORK, A CORPORATION OF NEW YORK.

BRUSH.

1,066,361.

Specification of Letters Patent.

Patented July 1, 1913.

Application filed October 30, 1911. Serial No. 657,417.

To all whom it may concern:

Be it known that we, MILTON W. ALEXANDER and JAMES W. BRADSHAW, each a citizen of the United States, the said MILTON W. ALEXANDER residing at Albany, county of Albany, and State of New York, and the said JAMES W. BRADSHAW residing at Troy, county of Rensselaer, and State of New York, have invented certain new and useful 10 Improvements in Brushes, of which the following is a specification.

The invention relates to such improvements and consists of the novel construction and combination of parts hereinafter described and subsequently claimed.

Reference may be had to the accompanying drawings, and the reference characters marked thereon, which form a part of this specification.

20 Similar characters refer to similar parts in the several figures therein.

Figure 1 of the drawings is a view in side elevation, partly in section, of a brush made in accordance with our invention. Fig. 2 25 is a plan view of the recessed side of the brush-back. Fig. 3 is a top plan view of the bristle-supporting pad provided with an edge-binding of fibrous material ready for insertion in the recessed back. Fig. 4 is a 30 view in cross-section on an enlarged scale of a portion of the bristle-supporting pad.

The invention relates to a type of toilet-brush in which the bristles are supported by an elastic pad or sheet which is inserted and 35 secured in a recess in the brush-back, and preferably so confined by the walls of the recess that the pad is held in a buckled position so as to present an outwardly curved or convexed surface from which the bristles 40 divergently project.

The principal object of the present invention is to more effectively and securely hold the edges of the pad within the recess in the brush-back.

45 Other objects will appear in connection with the following description.

Referring to the drawings wherein the invention is shown in preferred form, 1, represents the brush-back formed with a recess, 50 2, of a form and size adapted to receive the bristle-supporting pad, 3, to which the bristles, 4, are attached. The bristles may be attached to the pad, 3, in any known manner. The pad, 3, is formed of elastic material,

preferably soft rubber, and is of such a size 55 that when its edge has been forced into the recess, 2, in the brush-back, the pad will be buckled or curved outwardly, presenting a convexed outer surface from which the bristles divergently project, as shown in 60 Fig. 1. The walls of the recess, 2, may be of any form suitable for properly supporting the edge of the pad. In the drawings a preferred form of recess is shown, the wall of which is undercut to form a groove, 5, well 65 adapted to receive the inserted edge of the pad. The edge of the pad is provided with a binding of fibrous material, and the bound edge of the pad is glued or cemented to the wall of the recess in the brush-back, whereby the pad is securely retained in position in 70 the brush.

We have shown the pad covered with woven fabric, 6, which fabric is in the preferred form of the invention cemented to 75 the rubber pad and extends over the edge of the pad to form a binding therefor. The pad is also shown provided with an edge-binding of threads of fibrous material applied to the edge of the pad in the form of 80 over-edge stitching, said threads forming a binding for the edge of the pad, and also serving to more firmly secure the fabric, 6, to the pad along its edge. If desired the fabric may be omitted, and the binding 85 formed by the over-edge stitching alone relied upon to insure the necessary adherence of the edge of the pad to the walls of the recess in the brush-back. The pad may be provided with an edge-binding of fibrous 90 material in any known manner.

In assembling the parts of the brush, a coating of glue or cement is applied to the walls of the recess or to the bound edge of the pad, or both, and the pad is forced into 95 the recess until its edges are firmly seated therewithin. When the glue or cement has hardened, the pad will be securely held to the brush-back and within the recess by the adherence of its fibrous edge-binding to the 100 walls of the recess.

The brush-back may be made of wood or other material of which brush-backs are ordinarily made.

What we claim as new and desire to secure 105 by Letters Patent is—

1. A brush comprising a brush-back provided with a recess, and a bristle-supporting

pad of elastic material secured within said recess, said pad having a fibrous edge-binding adherent to the walls of said recess.

2. A brush comprising a brush-back provided with a recess, and a bristle-supporting pad confined within said recess, said pad having an edge-binding or woven fabric overstitched with fibrous thread, said binding being adherent to the walls of said recess.

3. A brush comprising a brush-back provided with a recess formed with an undercut grooved wall, and a bristle-supporting pad of elastic material confined in curved form within said recess, the edge of said pad being bound with fibrous thread stitched thereover, said thread being adherent to the walls of said groove.

4. A brush comprising a brush-back provided with a recess formed with an undercut grooved wall, and a bristle-supporting

pad of elastic material confined in curved form within said recess, the edge of said pad being bound with fibrous thread stitched thereover and exposed on the outer side of 25 the pad, said thread where exposed on the outer side of said pad being adherent to the undercut wall of the recess.

5. A brush comprising a brush-back provided with a recess and a bristle-supporting 30 pad of elastic material secured within said recess, said pad having a fibrous thread stitched over its edge and adherent to the wall of said recess, said thread being confined to the edge-portions of the pad. 35

In testimony whereof, we have hereunto set our hands this 26th day of October, 1911.

MILTON W. ALEXANDER.
JAMES W. BRADSHAW.
